(57) **CLAIM**

A new, original, ornamental design for a professional charging type controller, as shown.

DESCRIPTION

FIG. 1 is a perspective view of a professional charging type controller showing my new design;

FIG. 2 is another perspective view of a professional charging type controller showing my new design;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The cable is shown broken away in the drawings to indicate indeterminate length, it being understood that it has a uniform shape and appearance throughout its length.
